UNITED STATES PATENT OFFICE.

CHARLES WOLFF, OF CHICAGO, ILLINOIS, ASSIGNOR, BY MESNE ASSIGNMENTS, TO
WOLFF COAL SAVER COMPANY, A CORPORATION OF DELAWARE.

FUEL-SAVER.

1,348,919.

Specification of Letters Patent. Patented Aug. 10, 1920.

Application filed March 28, 1917. Serial No. 157,870.

To all whom it may concern:

Be it known that I, CHARLES WOLFF, a citizen of the United States, residing at Chicago, in the county of Cook and State of Illinois, have invented certain new and useful Improvements in Fuel-Savers, of which the following is a specification.

This invention relates to a device for use in connection with the draft system of a heating plant or furnace, and has for its object the provision of mechanism of this character which shall be of improved construction and more efficient in operation than similar devices previously known. The invention is exemplified in the combination and arrangement of parts shown in the accompanying drawing and described in the following specification, and it is more particularly pointed out in the appended claim.

20 In the drawing—

Figure 1 is a longitudinal section of a portion of a flue or smoke pipe to which the present invention is applied; and

Fig. 2 is a section on line 2—2 of Fig. 1. The numeral 1 designates a flue or smoke pipe as used in connection with any well known form of heating plants, such as stoves, furnaces and the like. The pipe 1 is provided with a plurality of openings 2 distributed around the entire periphery of the pipe and located as closely adjacent to the firebox as is practical. Although a single series of holes may be used, I prefer to provide a plurality of such series, as is shown in Fig. 1 of the drawing. A casing 3 surrounds the flue 1 and is attached thereto just below the series of openings 2. The upper end of the casing 3 is attached to the flue a considerable distance above the openings 2 as shown at 4 in the figure. The space between the flue 1 and the casing 3 is bridged at the lower end by an inwardly bent portion 5 and at the upper end by a similar portion 6. In this way a closed chamber is formed which surrounds the flue including the portion having the openings 2 and extending for a considerable distance above these openings. The casing wall 3 is provided near its upper end with a series of openings 7 formed by punching portions 8 from the sheet metal, leaving each portion 8 attached at its lower edge and bending it inwardly to form a deflector or baffle plate. Within the interior of the casing is

a deflector wall 9 secured to the bridge 6 by rivets 10 and having its lower edge 11 extending downwardly to a position spaced a slight distance from the lower bridge plate 5. The lower portion of the wall 9 is braced and held in position by brackets 12 distributed around the periphery of the device. Four of such brackets are shown in the embodiment illustrated in the drawing. A deflector plate 13 similar to 9 is located within the plate 9 and is secured at its lower end to the bridge plate 5 and has its upper edge 14 spaced downwardly from the plate 6. Brackets 15 hold the upper end of the plate 13 in place. By this arrangement it will be seen that air entering the openings 7 will first strike the plate 9 and will travel downwardly in the space between this plate and the outer wall 3, passing around the lower edge 11 of this wall and thence upwardly between the plates 9 and 13 and over the upper edge of plate 13. The current then moves downwardly between the plate 13 and the pipe 1 and finally enters the flue through the openings 2. It should be noted that the openings 7 are distributed around the entire periphery of the casing 3 and that the openings 2 are also distributed around the entire periphery of the flue 1, so that the current will be distributed around the entire periphery of the device during its movement up and down between the wall 3 and the flue 1 and will enter the flue 1 from all sides thereof.

To regulate the amount of flow, a ring 16 is supported by a bracket 17 secured to the wall 3, the ring 16 and bracket 17 being provided with openings 18 and 19 respectively arranged to register with the openings 7 in the wall 3. The bracket 17 is fixed relative to the wall 3, but the ring 16 is free to slide circumferentially around the bracket. The ring 16 is not continuous but is provided with lugs 20 at its ends through which a bolt 21 passes having a nut 22 by means of which the ring may be clamped in place upon the bracket 17. The effective size of the openings 19 may be varied by sliding the ring 16 upon the bracket 17. As will be explained, the amount of opening depends upon the characteristics of different furnaces and the conditions of operation, and by means of the arrangement just described, this amount can be regulated after

the apparatus has been installed and the ring 16 then clamped in place to retain the parts in proper position.

A damper 25 is located within the flue 1 above the inlet openings 2 and is provided 5 with an operating crank 26 by which its position in the flue may be changed. The supporting rods 27 are journaled in sleeves 28 secured to the sides of the flue and to 10 the wall 3. A check draft opening 29 is preferably located in the flue above the chamber formed by the casing 3, a cover 30 being provided for closing the opening when desired.

15 When the device is installed, it is preferably connected with the flue as near the firebox as the conditions will permit, and after it is in place the openings through 20 which air is admitted into the chamber within the casing 3, are adjusted in the manner described, while the fire is burning. It has been found by experience, that the size 25 of the openings 7 necessary to secure the best results depends upon a number of features and that where a flue is constructed to produce a strong draft, these openings will have to be greater than where a weaker draft is provided. For this reason it is desirable to adjust the size of these openings 30 after the apparatus is installed in each case the adjustment being made while the fire is burning, the regulation being such that the fire box will show the absence of excessive drafts and yet will be filled with quiet flame. 35 Either too great or too small an amount of opening is detrimental to the best results, and it is comparatively easy in each instance to find the exact position of the slide 16 which will produce the best results.

40 When the apparatus has been properly adjusted, and clamped in place, the decreased pressure within the flue 1 due to the rise of heated gases within the flue, will cause air to be drawn in through the openings 7 along the tortuous course previously 45 described and through the openings 2 into the flue. The space within the casing 3 forms a pre-heating chamber in which the air is heated before it is admitted to the flue. 50 The tortuous course provided for the passage of this air affords a large amount of heating surface and also retains the air within the preheating chamber for a considerable period of time before it is permitted to enter the flue, so that abundant 55 opportunity is provided for raising the temperature of the air before it is permitted to mingle with the gases arising from the combustion chamber.

60 It is somewhat difficult to ascertain all of the effects produced by the admission of preheated air through the openings 2 in the manner described, but there are at least two results which are apparent. One of 65 these is the supply of additional oxygen to

the partially burned gases arising from the combustion chamber for the purpose of producing more complete combustion. The position of the damper 25 above the openings 2 assists in the retention of the pre-heated air and the arising gases within the flue, and accomplishes to some extent at least, the return of these gases to the combustion chamber where more complete combustion takes place. Another effect and one which 75 is probably of greater importance, is the regulation produced by the in-flowing air through the openings 2, of the draft or current flowing upwardly in the flue 1.

In practical operation, it may be seen by 80 observing the fire within the firebox that when the proper regulation of the openings 7 is secured the current of air admitted through the preheating chamber acts as a cushion or retainer for holding the gases 85 within the firebox until combustion is completed and until these gases have transmitted their heat to the boiler or to whatever medium the furnace is designed for heating. Under such conditions the firebox shows a 90 mass of quiet flame free from rushing drafts and the flue temperature is many degrees lower than exists under the same conditions where the invention is not applied. The regulation of the draft is much more effective 95 than it is possible to attain by mechanical dampers, as has been shown by repeated experiments, in many cases the saving of fuel being as high as 25% over the best that could be obtained by the use of mechanical 100 dampers alone. One reason for the advantage of the air damper over the mechanical damper used alone, is that the air damper appears to automatically accommodate itself 105 to changing conditions of the fire and other forces which affect a given plant, when it has been once adjusted for that plant. If the draft in the flue for any reason increases, a greater amount of air will be drawn in through the preheating chamber and thus 110 the damping effect of the incoming current will be increased to resist the greater draft. If, on the other hand, the draft in the flue for any reason decreases, the amount of current through the preheating chamber will 115 decrease and the gases from the firebox will have a comparatively free passage through the flue. In this way an automatic balance is obtained and a uniform fire is insured, together with the retention of the gases in 120 contact with the surfaces designed to be heated thereby, until their heat has been transferred to these surfaces. The mechanical damper 25 may be used in the ordinary 125 way for regulating the draft when it is desirable to do so for the purpose of regulating the amount of heat produced in the furnace. This damper being located above the openings 2 also coöperates with the preheating chamber to hold the fresh air in con- 130

tact with the products of combustion and to prevent the free passage of the mixture of the two up the flue.

I claim:

5 In combination, a flue having openings therein spaced around the periphery thereof, a casing surrounding said flue to form an air preheating chamber and having openings therethrough spaced around the periphery thereof, means for varying the size of said openings through said casing to regulate the amount of air permitted to pass into said preheating chamber, means for 10 fixing said regulating means in adjusted positions, a damper within said flue above said openings for admitting air to said flue,

said damper being operable to regulate the size of the passage through said flue independently of the regulation of the openings for admitting air into said preheating chamber, and a plurality of baffle walls within said preheating chamber arranged with the opposite ends of alternating walls spaced from the ends of said chamber so that air entering said chamber must pass substantially the entire length thereof a plurality of times before entering said flue. 20 25

In testimony whereof I have signed my name to this specification on this 23rd day of March A. D. 1917.

CHARLES WOLFF.
